UNITED STATES PATENT OFFICE

2,538,447

EXTENSIBLE BRUSH CARRIED BY CLOSURE

Thelma A. Finney, Santa Ana, Calif.

Application November 18, 1947, Serial No. 786,674

2 Claims. (Cl. 15—140.4)

1

This invention relates to brushes and a holder therefor.

An object of this invention is to provide a brush and holder which are adapted to be mounted on a bottle or other receptacle having a threaded neck, such as a bottle containing nail polish or the like, so that the brush may have the bristles thereof disposed within the liquid irrespective of the depth of the liquid in the bottle.

Another object of this invention is to provide a brush and holder therefor, which is so constructed that the brush may be extended into or retracted from the liquid by means of an operator disposed on the outer end of the combined holder and cap.

A further object of this invention is to provide a combined brush holder and bottle cap which includes means for moving the brush endwise either into or out of the liquid within the bottle, the holder being so constructed that the device may be removed from the bottle with the brush extending from the inner or lower end of the holder for use in applying the liquid on the desired part.

With the above and other objects in view, my invention consists in the arrangement, combination and details of construction disclosed in the drawings and specification, and then more particularly pointed out in the appended claims.

In the drawings,

Figure 1 is a detail side elevation of a combined brush and holder constructed according to an embodiment of this invention,

Figure 2 is a longitudinal section of the device removed from the bottle,

Figure 3 is a sectional view taken on the line 3—3 of Figure 2, and

Figure 4 is a sectional view taken on the line 4—4 of Figure 2.

Referring to the drawings, the numeral 10 designates generally a conventional bottle of the type such as adapted to contain nail polish or the like.

The bottle 10 is formed with a neck 11 having conventional threads and a cap 12 is adapted to be threaded on the upper end of the neck 11. The cap 12 has extending upwardly therefrom an elongated tubular handle or shank 14, which is formed with a longitudinal bore 13.

The bore 13 is also formed with a spiral thread 15, the purpose for which will be hereinafter described.

A brush generally designated as 16 is adapted to be disposed in the bore 13 and includes an

2

elongated handle 17 having bristles 18' at its lower or inner end. The handle 17 slidably engages in a sleeve or lining 18 which is interposed between the handle 17 and the bore 13.

The sleeve or lining 18 is provided with a longitudinally extending slot 19 through which a pin or lug 20 which is fixed to the handle 17 is adapted to loosely engage. The pin or lug 20 engages in the thread 15 so that upon rotation of

10 the sleeve or lining 18 the handle 17 will be moved endwise in the shank or handle 14.

The upper or outer end of the sleeve 18 has fixed thereto a knob or operator 21 which is formed with a crimped flange 22 loosely engaged about an annular rib 23 carried by the outer end of the handle or shank 14. The crimped flange 22 is adapted to hold the sleeve 18 against endwise movement in the bore 13.

The handle 17 of the brush 16 has fixed thereto a collar 24, which, when the brush 16 is retracted into the handle 14, is adapted to bear against the outer end of the cap 12.

In the use and operation of this invention, the cap 12 is adapted to be threaded onto the neck 11 of the bottle 10 and the brush 16 is adjusted endwise so that the bristles 18' will project into the liquid but no portion of the handle 17 of the brush will be extended into the liquid.

When it is desired to use the brush 16, the cap 12 with the handle or shank 14 is unthreaded from the neck 11 of the bottle. Normally a substantial portion of the handle 17 will project from the lower end of the cap 12, but if a greater length of handle is desired, the knob or operator 21 is rotated to move the handle 17 downwardly and outwardly from the cap 12.

In Figure 1, the brush is shown in dotted lines extended to substantially the bottom of the bottle 10 when the liquid level is quite low in the bottle.

Having thus described my invention, what I claim is:

1. A brush holder for mounting on the threaded neck of a bottle, comprising a cap, an elongated handle extending from said cap, said handle being formed with a threaded bore, a sleeve rotatably engaging in said bore, a knob fixed to said sleeve at the outer end thereof, said handle being formed with an annular rib at the outer end thereof, a crimped flange carried by said knob rotatably engaging said rib, said sleeve having a lengthwise slot therein, a brush member including an elongated handle loosely engaging in said sleeve, a pin fixed to said brush handle projecting through said slot, and engaging the

thread of said first-named handle whereby rotation of said sleeve will effect endwise movement of said brush.

2. A brush holder for mounting on the threaded neck of a bottle, comprising a cap, an elongated handle extending from said cap, said handle being formed with a threaded bore, a sleeve rotatably engaging in said bore, a knob fixed to said sleeve at the outer end thereof, said handle being formed with an annular rib at the outer end thereof, a crimped flange carried by said knob rotatably engaging said rib, said sleeve having a lengthwise slot therein, a brush member including an elongated handle loosely engaging in said sleeve, a pin fixed to said brush handle projecting through said slot and engaging the thread of said first-named handle whereby rotation of said sleeve will effect endwise movement of said brush, and a collar fixed to said brush handle engageable with the lower end of

said first named handle for limiting the retraction of the brush handle with respect to said first-named handle.

THELMA A. FINNEY.
